W. BARTHOLOMEW.
WASHING MACHINE CYLINDER.
APPLICATION FILED OCT. 23, 1915.

Patented July 13, 1920.

Sheridan, Wilkinson and Scott, Atty's

UNITED STATES PATENT OFFICE.

WILLIAM BARTHOLOMEW, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

WASHING-MACHINE CYLINDER.

1,346,291.

Specification of Letters Patent. Patented July 13, 1920.

Application filed October 23, 1915. Serial No. 57,461.

To all whom it may concern:

Be it known that I, WILLIAM BARTHOLOMEW, a citizen of the United States, residing at Chicago, in the county of Cook and

5 State of Illinois, have invented certain new and useful Improvements in Washing-Machine Cylinders, of which the following is a specification.

My invention relates in general to cylinder washing machines, and more particularly to an improved cylinder for washing machines.

In the use of washing machines having a rotary cylinder comprising wooden perforated staves, it frequently becomes necessary to renew some of the staves which have become worn through usage. Heretofore it has been customary to retain the ends of the staves around the peripheries of the 20 end walls of the cylinder by means of endless bands or hoops which must be adjusted to exert sufficient pressure upon the surrounding ends of the staves to retain them tightly secured in place. The use of the 25 endless hoops renders it necessary to entirely remove the same and the surrounding staves whenever it is desired to repair the cylinder by replacing worn staves with new ones.

A primary object of my invention is to 30 provide a cylinder for washing machines, the parts of which will be so constructed as to securely retain them in assembled condition, but will permit the convenient replacement of worn parts without disturbing 35 the normal relative positions of the heads or getting the trunnions out of alinement.

A further object of my invention is to provide a cylinder for washing machines in which the staves are secured by overlying 40 straps arranged circumferentially around the ends of the cylinder, with each strap covering but a small group of staves, so that no stave is dependent solely upon its own bolts to prevent displacement, but is secured, 45 through the medium of the strap, by the several bolts which hold adjacent staves; and notwithstanding this method of securing the staves, a worn stave may be replaced without releasing more than a minimum 50 number of staves, and a sufficient number will always be left undisturbed in supporting relation to the heads to retain the accurate positions thereof and prevent the trunnions from getting out of alinement.

55 A still further object of my invention is

to provide a cylinder for washing machines which will be simple in construction, comparatively inexpensive in manufacture, and durable in use.

My invention will be more fully disclosed 60 hereinafter with reference to the accompanying drawing, in which the same is illustrated as embodied in a convenient and practical form, and in which,—

Figure 1 is a perspective view;

Fig. 2 is an end elevation of a portion of the cylinder;

Fig. 3 a perspective view of one of the retaining plates;

Fig. 4 a perspective view of one of the 70 tie-bars;

Fig. 5 a perspective view of one of the perforated staves; and

Fig. 6 an enlarged detail perspective view.

Similar reference characters are used to 75 designate similar parts in the several figures of the drawing.

Reference letter A designates the frame at one end of the cylinder from which concentrically projects a trunnion B for rotatably supporting the cylinder. The frame A comprises radial arms C, at the outer ends of which is supported a flange D. The spokes and flange of which the frame A is composed are preferably formed in an integral casting, to the inner surface of which is secured a plate A¹, which, together with the said frame, forms the end wall of the cylinder. It will be understood that a frame such as above described is located at 90 each end of the cylinder.

Tie-bars E are located in spaced relation around the end wall of the cylinder, the ends of such bars being preferably seated in recesses *d* in the flange D in radial alinement with the radial arms C. Located intermediate the adjacent tie-bars E are perforated staves F, the ends of which overlie the portions of the flange D intermediate the arms C. Overlying the outer ends of 100 the staves and tie-bars, and alining with the flange D of each end wall of the cylinder, are straps G circumferentially arranged around the ends of the cylinder. Bolts *g* extend through the straps G and underlying 105 portion of the flange D, and also through the interposed ends of the staves F and tie-bars E. The bolts therefore serve to removably secure the sections of the hoops G to the flange and to also tightly secure the 110

ends of the staves and tie-bars to the end frames of the cylinder. Since each strap receives a plurality of bolts, each stave is rendered safe by the strap that overlaps it even though it should lose its own bolt or nut; yet the number of bolts to be removed in releasing any one stave is relatively small, and the number of staves released in getting out a worn stave will not disturb 10 the two heads or get the trunnions out of alinement.

In order to increase the security of the connection between the ends of the tie-bars and staves, and the flanges of the end frames of the cylinder, outwardly projecting ribs d^1 may be provided around the inner edges of the flanges which extend into grooves e and f formed in the overlying end portions of the tie-bars E and staves F , respectively, 15 and these coöperate with the hold-down straps G to prevent a stave getting free in case it loses its bolt.

In order to permit access to the interior of the cylinder a door H is provided, which 20 is composed of perforated staves secured together by means of hinges K , the ends of the hinges preferably extending beyond the swinging edge of the door so as to overlie the adjacent tie-bar E and serve as stops to limit the closing movement of the door. The portion of the flange on each of the 25 end walls, which alines with the space occupied by the door, is projected outwardly, as shown at D^1 , so as to lie flush with the outer surface of the cylinder, formed by the staves and tie-bars. The sections of the surrounding hoops which aline with the sides of the door are secured to the underlying 30 outwardly projecting portions D^1 of the flanges of the end walls, such sections of the hoops serving as keepers to overlie the bolts of the fastening devices L of the doors.

When any of the staves become worn 35 they may be readily replaced by new ones by merely removing the securing bolts g of the particular sections of the hoops G which overlie the worn staves. In such operation the sections of the hoops which overlie the 40 ends of the staves which are not worn do not have to be removed, and hence the cylinder remains in its assembled condition, except as to the group of staves containing the worn ones which it is desired to replace. 45 After the new staves have been placed in position the sections of the hoops are placed upon their ends and the bolts g again inserted in position so as to extend through the sections thereof, the interposed ends of 50 the staves and the underlying portions of

the flanges D . By forming the hoop in sections the ends of the staves may be at all times firmly retained in engagement with the flanges on the end walls of the cylinder, as it is merely necessary to adjust the bolts 65 of the several sections in order to maintain the staves rigidly connected in position. The sections of the hoops also serve to prevent the heads of the bolts from working into the wood of which the staves are 70 formed, an objection which occurs in the use of wooden cylinders for washing machines as heretofore constructed.

From the foregoing description it will be observed that I have invented an improved 75 cylinder for washing machines, the parts of which are so constructed and assembled as to permit of the convenient replacement of any of the staves which may become worn in usage; it will be further observed that 80 the parts of my improved cylinder may be at all times retained firmly secured together by merely adjusting the fastening devices which secure the separate sections of the hoops, and the underlying series of staves, 85 to the end walls of the cylinder.

What I claim is:—

1. In a cylinder for washing machines, the combination with end walls, of staves overlying at their ends the peripheries of 90 said end walls, hoops formed in sections surrounding the ends of the staves, the corresponding sections of the hoops overlying the opposite ends of the same staves, and means for separately detachably securing the 95 sections of the hoops to the end walls.

2. A trunnioned cylinder for washing machines, comprising end walls carrying the trunnions upon which the cylinder revolves, tie-bars and staves overlying, at their ends, 100 the peripheries of said end walls and connecting and tying said end walls together, straps arranged circumferentially around the ends of the cylinder, each strap covering but a small group of staves, and bolts 105 extending through the ends of the tie-bars and staves and through the straps and end walls, whereby a stave is released by the removal of only those bolts which secure the strap which overlies it, and the remaining members are left intact to maintain integrity of the structure and alinement of its 110 trunnions.

In testimony whereof I have subscribed my name.

WILLIAM BARTHOLOMEW.
